COMBINED WALL FURNITURE CABINET AND FOLDABLE TABLE UNIT

Frank W. Geier, Vineland Station, Ontario, Canada

Filed Oct. 2, 1967, Ser. No. 8,831

Term of patent 14 years

Int. Cl. D6—01

U.S. CL. D33—19

Fig. 1

Fig. 2

FIG. 1 is a front perspective view of a unit in accordance with the invention and in the opened position.

FIG. 2 is a plan view from above of the embodiment of FIG. 1, and

FIG. 3 is a perspective view of the unit of FIGS. 1 and 2 in the closed position.

I claim:

The ornamental design for a combined wall furniture cabinet and foldable table unit, as shown and described.
